Primary Examiner — Darcey E Gottschalk*Assistant Examiner* — Vanessa M. Pursley(74) Attorney, Agent, or Firm — Barnes & Thornburg LLP; Jeffrey R. Stone(57) CLAIM

The ornamental design for a bottle, as shown and described.

DESCRIPTION

FIG. 1 is a front view of a bottle showing my new design; and,

FIG. 2 is a bottom view thereof.

In the drawings, the broken lines depict portions of the bottle that form no part of the claim.

1 Claim, 2 Drawing Sheets(56)
